NEEDLE LOOM

Application filed April 12, 1930. Serial No. 443,657.

This invention relates to looms and more particularly to mechanism for operating the weft inserting needles.

Needles have been employed heretofore in various types of looms to insert the weft threads, and in some needle looms all of the weft threads are inserted by a needle or needles, while in other constructions some of the weft threads are laid by one or more needles while the remaining weft threads are laid by a shuttle or shuttles.

These needles have been operated heretofore from a going part of the loom by mechanical connections between the needle and operating part of the loom, and while such mechanical connections operate the needles more or less satisfactorily for many weaving operations, they are open to the objection that they cannot be readily adjusted to vary the speed at which the needle is operated or the timing of its operation relative to the lay movement or other moving part of the loom.

The present invention therefore relates to a novel construction in which the needle is operable from a separate and distinct source of power from that employed to drive the loom, and as a result the operation of the needle may be readily controlled to conform to any variations that may be produced in the loom operation.

One important feature of the present invention resides in a hydraulically operated weft inserting needle. Another feature of the invention resides in an electric motor operable independently of the driving mechanism for the loom to control the needle operation.

Another feature of the invention resides in a loom provided with one hydraulic means for inserting the needle in the shed and a second hydraulic means for retracting the needle.

A further feature of the invention resides in means controlled by a going part of the loom for initiating and timing the hydraulic movement of the needle.

A further feature of the invention resides in means whereby the mechanism for controlling the operation of the needle may be

readily varied to conform to changes that may be made in the loom operation.

Still a further feature of the present invention resides in means for controlling the power operation of the needle so as to synchronize the needle movement with the operations of the loom.

As a result of the present invention whereby the needle is operated by a source of power that is separate and independent of the driving mechanism for the loom the starting and stopping of the needle and the speed of its movement can be readily controlled in any desired timed relation with the loom operation. Furthermore the hydraulic operation of the needle gives a smooth and quiet movement, and while the needle operating mechanism of the present invention may be used upon various forms of needle looms, it is particularly well adapted for use upon looms of extreme widths.

Other features of the invention and novel combination of parts in addition to the above will be hereinafter described in connection with the accompanying drawings which illustrate one good practical form of the invention.

In the drawings:—

Fig. 1 is a perspective view of a needle loom provided with the needle operating mechanism of the present invention;

Fig. 1^a is a transverse sectional view through the needle and its supporting means;

Fig. 2 on an enlarged scale is an end elevation of the parts shown in Fig. 1;

Fig. 3 is a vertical sectional view taken on the line 3—3 of Fig. 2;

Fig. 4 is an enlarged vertical sectional view taken on the line 4—4 of Fig. 3;

Fig. 5 is a side view of mechanism for synchronizing the movement of the lay and needle actuating mechanism;

Fig. 6 is an end view of the mechanism of Fig. 5;

Fig. 7 is a side elevation of mechanism for actuating one of the oscillating elements of Fig. 5 from the loom cam shaft;

Fig. 8 is a perspective view of means for

connecting the operating cable to the needle; and

Fig. 9 is a diagrammatic view of the wiring for controlling the loom operating motor and the needle operating motors.

The needle operating mechanism of the present invention is illustrated in connection with an Axminster loom of well known construction but it will be understood that the features of the present invention may be employed in connection with various types of looms having a weft needle.

The loom shown has the end frames 1 for supporting the operating parts, and at the front of the loom is provided the usual breast beam 2 adjacent which is supported the spike of take-up roll (not shown) but which is driven by the worm gear 3. At the rear of the breast beam is provided the usual lay 4 supported for movement toward and from the front of the loom, and the shed is formed by shifting the harnesses 5. The pile producing tufts are supplied to the fabric by the tuft tube frames 6 carried by the chains 7 as usual, and the tuft forming yarns are severed by the knives 8 and 9. The loom is driven by an electric motor 10 mounted upon the loom frame and having the pinion 11 which drives the large gear 12 adapted to operate the various parts of the loom, in a well known manner.

In the embodiment of the invention shown the weft inserting needle 13 and its operating mechanism is supported separately and independently of the loom frame, and to this end these parts are mounted upon the supporting frame 14 disposed in spaced relation to the side frame 1 of the loom as will be apparent from Fig. 1, and the lower ends of the legs 15 of the frame 14 are shown as bolted to a base plate 16.

The needle 13 in the construction shown is slidably mounted in the slotted tube 17 which is supported by spaced brackets 18 secured to the upper face of the frame 14, and the brackets 18 are provided with the anti-friction rollers 19 adapted to support the weight of the needle.

The means shown for moving the needle 13 lengthwise of the tube 17 into and out of the shed consists of a cable 20 the upper run of which is supported by the grooved pulleys 21, 22 disposed near the opposite ends of the tube 17 and the rollers are supported by the brackets 23, 24. The cable 20 passes from the pulleys 21, 22 about the grooved pulleys 25 supported by brackets secured to the frame 14 and then downwardly about the grooved operating drum or scroll 26, the ends of the cable being adjustably secured to the drum to vary the cable tension. The needle 13 is connected to the operating cable 20 by providing the needle with the laterally extending plate 27 having the removable section 28

adapted to be firmly clamped against the cable as shown in Fig. 1^a.

It will be apparent from the needle operating means so far described that the needle 13 may be moved into the shed by rotating the drum 26 in one direction and may be retracted by rotating the drum in the opposite direction. The drum 26 is rigidly secured to the transversely extending shaft 29 which is journaled in bearings mounted upon the frame 14 and the shaft 29 is provided with an operating pinion 30.

The needle shown is relatively long since it is associated with a wide loom, and it is therefore necessary to impart a long stroke to the needle. The drum operating pinion 30 is therefore shown as operated by a toothed sector 31 which is rigidly secured to and supported by the shaft 32 journaled in bearings secured to the upper portion of the supporting frame 14. The shaft 32 is provided with the operating gear 33, the arrangement being such that the rotation of the gear 33 through a small angle will operate through the connections described to move the needle a substantial distance.

As above stated an important feature of the present invention resides in hydraulic means for operating the needle 13. It is apparent that the hydraulic operating mechanism may be variously constructed and the means shown consists of two independently operable hydraulic devices, one being provided to insert the needle and the other to retract the needle. The arrangement is such that the speed and timing of the needle insertion and retraction may be controlled independently to accommodate any desired condition of loom operation.

In the construction illustrated the operating gear 33 is rotated in one direction by a rack 34 and in the opposite direction by the rack 35. These racks are disposed at the opposite sides of the gear 33 and are supported by guide-ways 36 and antifriction roller 37 for vertical sliding movement. The rack 34 has its lower end secured by means of a bolt 38 to a transversely extending bar 39 of the hydraulic operating device 40, and the rack 35 has its lower end similarly secured to the bar 39 of the hydraulic operating device 41.

The hydraulic devices 40 and 41 are or may be similar in construction and may operate in a well known manner, the description of one will therefore suffice for both.

As will be apparent from Fig. 4 the hydraulic device 40 consists of the oil containing cylinder, the lower end 42 of which may rest directly upon the base plate 16 and may be secured thereto by means of the clevis 43. Within this cylinder is slidably mounted the piston 44 having the upwardly extending push rods 45 that extend through oil tight bushings 46 mounted in the cover plate 47.

of the cylinder and the upper ends of the rods 45 are secured to the cross bar 39.

Movement of the piston 44 within the cylinder is produced by causing the oil 48 to flow from one side of the piston to the other through the oil ducts 49 formed in the piston and which communicate with the oil passage 50 formed in the piston above and below the ducts 49 and constructed to communicate 10 with the oil chamber above the piston.

The arrangement is such that if the oil is caused to flow from the upper chamber through the piston, as indicated by the arrows, into the lower chamber, the piston will 15 be forced upwardly by the oil pressure below the piston, while if the oil is caused to flow in the opposite direction in the ducts 49 the piston will be lowered.

In the hydraulic construction illustrated it 20 is not necessary to provide operating valves to control the movement of the piston 44, since this is accomplished by providing a rotating propeller or pump 51 that rotates within a clearance space formed in the central portion of the piston, as shown in Fig. 4. The propeller 51 is supported and driven by the splined shaft 52, the lower portion of which is journaled in a bearing 53 secured to the upper portion of the piston 44. The 25 shaft 52 is driven by a small motor 54 the rotor 55 of which is provided with a hollow shaft adapted to slidably or telescopically receive the splined shaft 52. The motor 54 is mounted upon the cylinder head 47, the arrangement being such that when the propeller 51 is rotated by the motor 54 to hydraulically lift the piston 44, the shaft 52 will slide upwardly within the rotor shaft 55.

It will be seen from what has just been 40 said that when it is desired to move the rack 34 upwardly to move the needle 13 in one direction, this may be accomplished by starting the motor to drive the propeller 51 and cause it to force the piston 44 upwardly. 45 The motor 54 may be variously constructed but as shown is adapted to be operated from the three-phase circuit to be described.

When the propeller 51 is not being rotated by its motor the piston 44 may be forced 50 downwardly in its cylinder by exerting a downward pressure upon the cross bar 39, as this will cause the oil to pass from below the piston to above the piston through the ducts 49 and passages 50 in the opposite direction to that indicated by the arrows in Fig. 4. The movement of the piston 44 downwardly is arrested at the end of its stroke, without producing a sudden shock or jar, by providing in the lower portion of the cylinder 55 the baffle ring 56 supported by the springs 57, the arrangement being such that this baffle will close the entrance to the ducts 49 just before the piston strikes the lower end of its cylinder.

60 The hydraulic movement of the piston 44

is an upward direction is arrested by the stop spacers 58 the upper ends of which are adapted to engage abutments upon the piston head 47. The operation of the device is such that if the upward movement of the piston is arrested at any point along its path of travel, the motor will continue to rotate and force the oil from one passage 50 to the other to support the piston in that position.

The hydraulic device 40 operates in the 75 manner described to raise the rack 34 to insert the needle 13, and the hydraulic device 41 operates in a similar manner to raise the rack 35 to retract the needle, it being understood that the device 41 is provided with an operating motor 59 similar to the motor 54 above described. One of the motors 54, 59 remains idle while the other operates, and as the operating motor forces its piston and rack upwardly the gear 33 will move the 80 other rack downwardly to lower the piston connected thereto.

It will be seen from the foregoing that the needle movement may be controlled as desired by starting and stopping the motors 54, 59, but it is essential that the movement of the needle be accurately timed and synchronized with the loom operation, and this is satisfactorily accomplished by the electrical connections which will now be described.

The motor 10 for driving the loom may be operated from the same circuit as the motors 54, 59, but when the loom to be driven is large and heavy the motor 10 preferably is constructed to be operated from a three-phase 100 circuit of higher voltage than that supplied to the motors 54, 59. The main current supply wires for the motor 10 are indicated in the diagrammatic view of Fig. 9 by A. These wires are connected to the motor 10 by 105 the conductors A¹, A², A³ provided with the hand operated switch 60.

The starting and stopping of the motor 10 to start and stop the loom may be controlled by the electrically operated switch M having 110 the three switch elements shown and which are mechanically connected to cause the circuits of the conductors A¹, A², A³ to be simultaneously closed or opened.

The switch M is preferably controlled by 115 a solenoid or control coil S, the arrangement being such that the switch M will be closed and held closed as long as the solenoid S is excited but will open automatically when the current to the coil S is cut off. The solenoid S is included in the circuit formed by the wires a, b, c, d connected to the conductors A², A³ and in this circuit is included the normally open start button or push button 61 located at any convenient point upon the loom, the construction of this button being such that it may be manually actuated to close the circuit in which it is included but will open the circuit as soon as it is released. It therefore follows that when the button 61 120

is actuated it will close the circuit *a, b, c, d* and excite the coil *S* to close the switch *M* and start the motor 10.

In order to prevent the switch *M* from opening as soon as the button 61 is released, the switch *M* is provided with the auxiliary switch element 62 controlled by the switch *M* and adapted to complete the circuit between the conductor *A³* and the wire *e* when the switch *M* is closed. The arrangement is such that as soon as the push button 61 is actuated to close the switch *M* the circuit through the wire *e* will be completed and current will be supplied to the solenoid through this conductor after the push button 61 is released. The loom may be stopped by actuating either of the normally closed push button switches 63, 63' included in the circuit *e, b, c, d* to cut off the supply of current to the coil *S*. It is desirable to stop the loom in case either an overload or under-voltage occurs in the main circuit *A*, and this is accomplished by including a thermal relay switch *R* in the coil controlling circuit *c, d*. The switch element *R* which may be constructed in a well known manner is provided with the coils *f* shown as connected in the circuits *A¹, A³*, the arrangement being such that opening of the relay switch *R* caused by an abnormal flow of current will open the switch *M* and stop the loom.

The switch mechanism so far described controls the loom operating motor 10. The motors 54 and 59 for operating the needle 13 are supplied with current from a main line *B* of the same or lower voltage than that supplied by the line *A*. The main line *B* is connected by the conductors *B¹, B², B³* to the magnetically controlled switch 64 for the motor 54, and the magnetically controlled switch 65 for the motor 59. The switch 64 is connected to the motor 54 by the conductors *B⁴, B⁵, B⁶* and the switch 65 is connected to the motor 59 by the conductors *B⁷, B⁸, B⁹*. The switch 64 is controlled by the solenoid or magnetic coil 66 and the switch 65 is controlled by the similar coil 67.

It will be apparent from what has just been said that when the solenoid 66 is excited it will close the switch 64 and this will operate the motor 54 to insert the needle, and when the solenoid 67 is excited it will close the switch 65 and operate the motor 59 to retract the needle.

The operation of the switches 64, 65 should be accurately controlled in timed relation with the lay movement of the loom, and to this end in the construction shown a timing switch 68 operated from the loom cam shaft 69 is included in the circuit *g, h* connected to the solenoid 66, and a similar timing switch 70 also operated from the cam shaft is included in the circuit *i, j* leading to the solenoid 67. Each of the timing switches shown

has three angularly spaced contact surfaces 71 adapted to be engaged by the contact brush 72 to close the circuit in which the timing device is included. The arrangement is such that rotation of the cam shaft 69 will cause one of the surfaces 71 of the timing device 68 to engage the brush 72 throughout the needle inserting period, and will cause one of the surfaces 71 of the timing device 70 to engage the brush 72 throughout the needle with drawing period.

While the mechanism just described will cause the needle insertion and reaction in timed relation with the loom, it is desired to provide means controlled by the needle movement to cut off the current to the needle operating motor when the needle has reached the end of its stroke in either direction. To this end in the construction shown the normally closed switch 73 is included in the circuit for the solenoid 66 and the normally closed switch 74 is included in the circuit for the solenoid 67. The switch 73 is positioned to be engaged by an adjustable stop 75 which is shown as secured to the needle, and the switch 74 is positioned to be engaged by an adjustable stop 76 carried by the needle or a part controlled thereby. The arrangement is such that when the needle is fully inserted in the shed the stop 75 opens the switch 73 and stops the motor 54, and when the needle is fully retracted the stop 76 opens the switch 74 and stops the motor 59.

It is desirable that means be provided for automatically opening the switches 64 and 65 to stop the needle operating motors whenever the loom operating motor 10 is stopped, and this is accomplished by placing the circuits for the solenoids 66 and 67 under the control of the loom motor switch *M*. The circuit for the solenoids is therefore provided with the conductors *k, l* having the switch 77 adapted to be moved to and from its closed position by the movement of the switch *M*. The arrangement is such that the circuit for controlling the solenoids will be supplied with current only when the switch *M* for the loom motor is closed, and as a result the needle control motors 54 and 59 can be operated only when the loom is running.

If the needle 13 should fail from any cause to withdraw in time, the customary detector mechanism operating in conjunction with the control for the loom motor 10 will promptly stop the loom to prevent a smash.

In addition to the controls above described for the motors 54, 59 it is desirable to provide means for synchronizing the movement of the needle with the movement of the rocker shaft or other oscillating part of the loom to insure proper operation of the needle. This is accomplished in accordance with the present invention by providing the circuits for the solenoids 66 and 67 with switch mechanism consisting of contacts one of which oscillates

back and forth in time relation with the needle movement and the other oscillates back and forth in timed relation with the rocker shaft movement.

5 The means shown to this end in Figs. 5 and 6 and more or less diagrammatically shown in Fig. 9 consists of a contact 78 carried by a bracket 79 mounted upon or connected to the shaft 32 of the needle inserting mechanism. The bracket 79 is provided with the coiled spring 80 which causes the bracket 79 to rotate with the shaft 32 but permits a limited angular movement therebetween. The contact 78 is connected by the conductor 15 81 to the contact ring 82 mounted upon the bracket 79 and adapted to be engaged by a brush 83.

The contact 78 is supported by its bracket between the spaced contacts 84, 85 adjustably 20 mounted upon a bracket 86 that oscillates back and forth under the control of the rocker shaft or cam shaft. The bracket 86 is supported by the shaft 87 and has a projecting operating arm 88 (see Fig. 7). Rocking movement is imparted to the arm 88 in the construction shown by a connecting link 89 connected to the pinion 90 driven by a relatively large bevel gear 91 secured to the cam shaft 69. The arrangement of the gears 90, 25 91 and other connections is such that the back and forth movement imparted to the bracket 86 by the cam shaft will correspond to the movement of the loom rocker shaft.

The contacts 84, 85 carried by the bracket 35 86 may be adjusted relative to the independently movable contact 78 to vary the space between the contacts 84, 85, and the contact 84 is connected by a conductor 92 to a contact ring 93 having the cooperating brush 94, 40 while the contact 85 is connected by a conductor 95 to a ring 96 having the cooperating brush 97. The bracket 86 is yieldingly connected to its operating shaft 87 by the coiled spring 98. The contacts 78, 84 and 85 and the 45 parts associated therewith are preferably enclosed in a casing 99, and the timing devices 68 and 70 are enclosed in a housing 100.

The contact brush 94 is connected to the solenoid 66 by the conductor *m* and the contact brush 97 is connected to the solenoid 67 by the conductor *n*. The contact brush 83 is connected to the conductor *o* leading from any suitable source of current supply such as one of the main conductors *B*. The conductor *l* is also connected to a suitable source of supply such as a second wire of the main conductors *B*. Sparking between the various contacts for controlling the switches 64, 55 65 is reduced by providing the condensers 101 one of which is connected between the wires *m*, *o* by the conductor *p* and the other is connected between the wires *n*, *o* by the conductor *q*.

The operation of the synchronizing switches just described is such that the mo-

tor 54 for inserting the needle will not be started until the bracket 86 has been moved by the loom in a direction to cause its contact 84 to engage the contact 78, and the motor 59 for retracting the needle will not be started until the bracket 86 has been moved in the opposite direction to cause the contact 85 to engage the contact 78. As a result of this construction only one motor 54, 59 will operate at a time and any variation in the synchronized movement of the needle and rocker shaft will cause the contact 78 to move relative to the contact 84 or 85 to correct this defect in the timing of the needle operation. It will be understood that as long as the contact 78 is advanced by the needle operating mechanism at the same speed at which the contact 84 or 85 is advanced by the loom, the circuit will be closed through the contacts, but a relative change in speed will disengage 85 these contacts to stop the motor 54 or 59.

It will be seen from the foregoing that the source of power for operating the weft needle is separate and independent from the source of power for operating the loom, and as a result the movement of the needle may be readily controlled to correspond to any condition of loom operations, since all that is necessary to accomplish this is to vary the speed of the operating motors and the adjustment of the switch mechanism for controlling the needle operation. For example: pronounced changes in the operation of the needle may be secured by changing the angular position of the timing switches 68, 70 upon the cam shaft 69 and the length of the contact faces 71. The position at which the needle is brought to rest at the end of its stroke may be varied by adjusting the stops 75, 76 and further changes may be secured by modifying the speed of the motors 54, 59.

What is claimed is:

1. In a loom, in combination, shed forming mechanism, a weft inserting needle, hydraulic mechanism for operating the needle to insert weft threads, and means for automatically synchronizing the hydraulic movement of the needle with the movement of the shed forming mechanism including a controller having cooperating parts, one of which is driven from the loom mechanism and the other from the needle operating mechanism, and means responsive to the movement of one of said parts relative to the other for controlling the operation of the needle.

2. In a loom, in combination, shed forming mechanism, a lay, a weft inserting needle, hydraulic means for operating the needle to insert weft threads, and circuit closing means controlled by the rotating movement of a part of the loom, and means controlled by said circuit for effecting the

hydraulic operation of the needle in timed relation with the lay movement.

3. In a loom, in combination, shed forming mechanism, a weft inserting needle, a hydraulic operated piston at the side of the loom for inserting the needle in the shed, a second hydraulic operated piston on the same side of the loom for removing the needle from the shed, and means for controlling the operation of each piston.

4. In a loom, in combination, shed forming mechanism, a weft inserting needle, a hydraulic operated piston for advancing the needle to insert weft threads, an electric motor for supplying the operating fluid to the piston, and means for controlling the operation of the motor from a going part of the loom.

5. In a loom, in combination, power means for operating the loom, shed forming mechanism operable by the power means, a weft inserting needle, separate power means including an electric motor for operating the needle, and means for controlling the operation of said separate power means from a going part of the loom and adapted to synchronize the needle movement with the loom operations.

6. In a loom, in combination, power means for operating the loom, shed forming means operable by the power means, a weft inserting needle, a motor separate from the loom driving means for operating the needle, and means for controlling said motor from a going part of the loom and adapted to synchronize the needle movement with the loom operations.

7. In a loom, in combination, power means for operating the loom, shed forming mechanism, a weft inserting needle, a motor separate from the loom driving means for inserting the needle and another motor for retracting the needle, and means controlled by a going part of the loom to operate said motors in timed relation with the loom operations.

8. In a loom, in combination, an electric motor for operating the loom, shed forming mechanism, a weft inserting needle mounted for movement into and out of the shed, a second electric motor for operating the needle, and switch mechanism controlled from a going part of the loom and adapted to actuate the second motor to operate the needle in timed relation with the loom operations.

9. In a loom, in combination, power means for driving the loom, shed forming mechanism operable from a going part of the loom, a weft inserting needle, a motor for operating the needle, switch mechanism controlled from a going part of the loom and adapted to actuate the motor to operate the needle in timed relation with the loom operations, and adjustable means associated with

said switch mechanism for varying the control of the needle.

10. In a loom, in combination, power means for driving the loom, shed forming mechanism, a weft inserting needle mounted for movement into and out of the shed, an electric motor operable to insert the needle in the shed, switch mechanism adapted to be operated from a going part of the loom to start the needle inserting motor, and means for stopping the motor when the needle is fully inserted.

11. In a loom, in combination, power means for driving the loom, shed forming mechanism operable from a going part of the loom, a weft inserting needle, an electric motor operable to insert the needle, a second electric motor operable to retract the needle, and switch mechanism operable from a going part of the loom to start the motors to insert and retract the needle in timed relation with the loom operations.

12. In a loom, in combination, power means for driving the loom, shed forming mechanism, a weft inserting needle, an electric motor operable to insert the needle, a second electric motor operable to retract the needle, switch mechanism operable from a going part of the loom to start the needle inserting motor, means for stopping the needle inserting motor when the needle is inserted, switch mechanism operable from a going part of the loom to start the needle retracting motor, and means for stopping the needle retracting motor when the needle is retracted.

13. In a loom, in combination, power means for driving the loom, shed forming mechanism operable from the power means, a weft inserting needle, an electric motor for operating the needle, switch mechanism operable from a going part of the loom to control the needle operating motor, and additional switch mechanism having a part actuated by a moving part of the loom and a part actuated by the needle operating mechanism to synchronize the loom operations and needle movement.

14. In a loom, in combination, power means for driving the loom, shed forming mechanism, a weft inserting needle, an electric motor for operating the needle, and switch mechanism adapted to cooperate with a moving part of the loom and a moving part of the needle operating mechanism to control and synchronize the needle movement with the loom operations.

15. In a loom, in combination, power means for driving the loom, shed forming mechanism, a weft inserting needle, an electric motor for operating the needle, switch mechanism operable from a going part of the loom to control the needle operating motor to actuate the needle in timed relation with the loom operations, and adjustable means asso-

ciated with said switch mechanism to accommodate the operation of the needle to uneven beats of the loom.

16. In a loom, in combination, power means for driving the loom, shed forming mechanism operable from the power means, a weft inserting needle, hydraulic operated means for actuating the needle, an electric circuit controlled from a going part of the loom and means controlled by said circuit, for effecting the hydraulic operation of the needle in timed relation with the loom operations.

17. In a loom, in combination, power means for driving the loom, shed forming mechanism, a weft inserting needle, hydraulic operated means for actuating the needle, and means controlled from a going part of the loom for effecting the hydraulic operation of the needle in timed relation with the loom operations, including electrical means operable by a going part of the loom and adapted to control the hydraulic operation of the needle.

18. In a loom, in combination, power means for operating the loom, shed forming mechanisms operable from a going part of the loom, a weft needle mounted for movement into and out of the shed, a separate and independent source of power for operating the needle, means for synchronizing the needle movement and loom operation, including a controller having a part actuated by the needle movement and a second part operable from a moving element of the loom, and means operable by the relative movement of said parts to modify the needle movement.

19. In a loom, in combination, power means for operating the loom, shed forming mechanism operable from a going part of the loom, a weft needle mounted for movement into and out of the shed, a separate and independent source of power for inserting the needle, a second separate and independent source of power for withdrawing the needle, and electric means for synchronizing the needle movements with the loom operations.

20. In a loom, in combination, power means for operating the loom, shed forming mechanism operable from a going part of the loom, a weft needle mounted for movement into and out of the shed, a separate and independent source of power for inserting the needle, a second separate and independent source of power for withdrawing the needle, and means for synchronizing the needle movement with the loom operations including a controller having a part actuated by the needle movement and a second part actuated by a moving part of the loom.

21. In a loom in combination, power means for driving the loom, shed forming mechanism operable from the power means, a weft inserting needle, hydraulic means for inserting and retracting the needle comprising a

pair of cylinders each having a hydraulically operated piston, a rotating shaft connected to the needle, a rack and gear connection between one piston and said shaft to rotate the shaft in the needle inserting direction and a rack and gear connection between the other piston and said shaft to retract the needle, and means for synchronizing the hydraulic movement of the needle with the loom operations.

22. In a loom in combination, power means for driving the loom, shed forming mechanism operable from the power means, a weft inserting needle, hydraulic means for inserting and retracting the needle comprising a pair of cylinders each having a hydraulically operated piston, a rotating shaft connected to the needle, rack and gear connections between the pistons and shaft to rotate the latter and arranged so that the hydraulic movement of one piston serves to depress the other piston, and means for synchronizing the hydraulic movement of the needle with the loom operations.

23. In a loom in combination, power means for driving the loom, shed forming mechanism operable from the power means, a weft inserting needle, hydraulic means for operating said needle including a cylinder having a hydraulic operated piston, a rotating shaft operatively connected to the needle, a rack and gear connection between the shaft and piston to operate the shaft, and means for synchronizing the hydraulic movement of the needle with the loom operations.

24. In a loom in combination, power means for driving the loom, shed forming mechanism operable from the power means, a weft inserting needle, hydraulic means for operating said needle including a cylinder having a hydraulic piston, means for imparting a multiplied movement from the piston to the needle including a rack connected to the piston and a large segmented gear actuated by the rack and operatively connected to the needle, and means for synchronizing the movement of the needle with the loom operations.

25. In a loom in combination, power means for driving the loom, shed forming mechanism operable from the power means, a weft inserting needle, hydraulic means for inserting and retracting the needle comprising a pair of cylinders each having a hydraulic operated piston operatively connected to the needle, a power operated pump for forcing a liquid into the lower portion of one cylinder to move the piston in a direction to insert the needle, a second power operated pump for forcing a liquid into the lower portion of the other cylinder to move its piston in a direction to retract the needle, and means for operating said pumps in timed relation with the needle movement.

26. In a needle loom, the combination of

- shed forming mechanism, a weft inserting needle, a rotating shaft operatively connected to the needle for inserting and withdrawing the needle, a gear operatively connected to the shaft for rotating it, hydraulic means for rotating said gear, comprising two hydraulic cylinders, a piston operating in each cylinder, a rack connected to each of the pistons and operatively connected to said gear for rotating it in one direction to insert the needle in the shed and then in the opposite direction to withdraw the needle from the shed.
27. In a needle loom, the combination of
- 15 shed forming mechanism, a weft inserting needle, hydraulic means for inserting the needle into the shed and withdrawing it therefrom comprising two cylinders each having a hydraulically operated piston, a rotating shaft operatively connected to the needle, and connection from the two hydraulically operated pistons to the said shaft for rotating it in one direction by movement of one of said pistons to insert the needle and
- 20 rotating it in the opposite direction by the other of said pistons to withdraw the needle.
28. In a needle loom, the combination of
- 25 shed forming mechanism, a weft inserting needle, hydraulic means for inserting and retracting the needle comprising two cylinders each having a hydraulically operated piston, a pump associated with each of the cylinders to impart operating movement to the pistons, connection between each piston and the weft
- 30 inserting needle, and means for controlling the operation of the two pumps to effect movement of the needle in one direction by one of said pistons and cause the other piston to move in its idle stroke to effect movement of the needle first in one and then in the opposite direction.
29. In a needle loom, the combination of
- 35 shed forming mechanism, a weft inserting needle, rotating means connected to the needle to effect its insertion into and withdrawal from the shed, hydraulic means for operating the rotating means first in one direction to insert the needle and then in the opposite direction to withdraw the needle, comprising
- 40 two cylinders each having a hydraulically operated piston connected to said rotating means, and devices to control the flow of fluid pressure in said cylinders that one of the pistons may be moved in its operating stroke to turn said rotating means to move the needle in one direction and effect idle movement of the other piston.
